[57]**CLAIM**

The ornamental design for a heel insert for a shoe sole, as shown and described.

DESCRIPTION

FIG. 1 is an elevational view of one side of a heel insert for a shoe sole showing my new design;

FIG. 2 is an elevational view of the other side thereof;

FIG. 3 is a top plan view thereof;

FIG. 4 is a rear elevational view thereof;

FIG. 5 is a cross sectional view taken along line 5—5 of FIG. 1;

FIG. 6 is a cross sectional view taken along line 6—6 of FIG. 1;

FIG. 7 is an elevational view of one side of a second embodiment of a heel insert for a shoe sole showing my new design;

FIG. 8 is an elevational view of the other side of the second embodiment;

FIG. 9 is a top plan view of the second embodiment;

FIG. 10 is a rear elevational view of the second embodiment;

FIG. 11 is a cross sectional view taken along line 11—11 of FIG. 7;

FIG. 12 is a cross sectional view taken along line 12—12 of FIG. 7;

FIG. 13 is an elevational view of one side of a third embodiment of a heel insert for a shoe sole showing my new design;

FIG. 14 is an elevational view of the other side of the third embodiment;

FIG. 15 is a top plan view of the third embodiment;

FIG. 16 is a rear elevational view of the third embodiment;

FIG. 17 is a cross sectional view taken through line 17—17 of FIG. 13; and

FIG. 18 is a cross sectional view taken through line 18—18 of FIG. 13.

The broken line showing of the remaining portions of the shoe sole and upper is for illustrative purposes only and forms no part of the claimed design.
